UNITED STATES PATENT OFFICE.

HENRY M. WRIGHT, OF DETROIT, MICHIGAN.

DESIGN FOR A SPOON.

SPECIFICATION forming part of Design No. 20,959, dated July 21, 1891.

Application filed June 11, 1891. Serial No. 395,989. Term of patent 3½ years.

To all whom it may concern:

Be it known that I, HENRY M. WRIGHT, a citizen of the United States, residing at Detroit, county of Wayne, State of Michigan, have invented and produced a new and original Design for Spoons; and I declare the following to be a full, clear, and exact description of the invention, such as will enable others skilled in the art to which it pertains to make and use the same, reference being had to the accompanying drawing, which forms a part of this specification.

The drawing shows a spoon embodying my design.

The design consists, essentially, in a spoon having at the extreme end of the handle a miniature statue of Cadillac. I show a handle with a spiral twist, but do not claim this twisted handle specially, the essential features of my invention being the statue of

Cadillac at the end of the handle. The special design of the statue is shown in the drawing.

In the drawing, A represents the bowl of the spoon, B the handle, and C the miniature statue of Cadillac at the end of the handle.

The Cadillac referred to in this description is La Motte Cadillac, the founder of Detroit.

What I claim is—

The design for a spoon herein shown and described, the same consisting of the spoon bowl and handle with a miniature statue of Cadillac at the extremity of the handle, as set forth.

In testimony whereof I sign this specification in the presence of two witnesses.

HENRY M. WRIGHT.
